UNITED STATES PATENT OFFICE

ALLEN H. KERNGOOD, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND

APPAREL BUCKLE

Application filed September 10, 1930. Serial No. 481,052.

The primary object of this invention is to provide a two-part slide or adjustable buckle, especially for use on washable fabric belts for apparel, both of which parts are capable 5 of being attached to the belt without sewing or other extraneous fastenings, the parts when engaged being free of liability to accidental disconnection.

The invention consists of a two-part 10 buckle, each part having a frame provided with cross-bars and an end bar about which the belt ends are looped and so secured, and one of said parts having a front end bar provided with a hook-engaged bar depressed 15 from the level of the frame, and the other part having a front end bar provided with a humped hook extending downwardly and reversely beneath the frame and adapted to engage the depressed portion of the front end 20 bar of the other part and be held in such engagement against accidental parting or dislocation, as I will proceed now more fully to explain and finally claim.

In the accompanying drawings illustrating the invention, in the several figures of 25 which like parts are similarly designated, Figure 1 is a perspective view showing the two parts of the buckle disengaged. Fig. 2 is a longitudinal section of the buckle mounted upon opposite ends of a belt, the ends 30 only of the belt being shown and the two parts of the buckle engaged.

The part shown at the right in the drawings, has any suitable frame. The frame 25 shown is composed of side bars 1 and 2, a rear end bar 3 and a front end bar 4, all on a substantially common level. The side bars are connected by a pair of parallel cross bars 5 and 6, arranged between the end bars 3 and 40 4, and depressed from the level of the frame. The front end bar 4 is cut back at 7 between its ends and toward the cross bar 6, and has, at its extreme front end, a hook-engaged 45 bar 8, which is depressed from the level of the frame. The bars 5 and 6 are separated from the end bars and from one another by the intermediate slots 9, 10 and 11, which serve to permit the looping and securing of the belt end and the part, as indicated in Fig. 2. The depressed bar 8 is spaced apart from the

remainder of the end bar 4 by the slot 12 which permits the engagement and disengagement of the hook with said bar 8.

The part shown at the left in the drawings, has any suitable frame, the one shown being 55 composed of the side bars 13 and 14, a rear end bar 15 and a front end bar 16, all on a substantially common level. The side bars are connected by a pair of parallel cross bars 17 and 18 arranged between the end bars 15 and 16 and depressed from the level of the frame. The front and rear end bars and the cross bars are separated by the slots 19, 20 and 21. The front end bar 16 has the forwardly extending hook 22 which is curved 60 downwardly and then rearwardly so as to underlie the frame, and at the bottom of the curve it is provided with an upstanding hump 23 which coacts with the bar 8 to lock the buckle parts against accidental disengagement when connected as shown in Fig. 2. The lip 24 of the hook extends, preferably 65 rearwardly beyond the front bar 16 so as to further the disengaging function of the hook and bar 8.

The parts are engaged by tilting one or the other, so that the lip of the hook may enter the slot 12 and the parts then turned to a common level, as indicated in Fig. 2. Disengagement is effected by a reverse movement 70 of the parts.

The parts may be die cut out of sheet metal, and stamped or pressed to shape. They may be ornamented as desired and finished according to order.

The ends of the belt are passed beneath the rear bars of the frame, up through the rear slots then over the two intermediate depressed cross bars, then around the front cross bars, then returned through the front slots and over the rear cross bars and then through the rear slots so as to be firmly pinched between the rear cross bars and the end bars of the frames, thereby avoiding 85 the necessity of serving or otherwise fastening such belt ends, and also admitting of the adjustment of the parts to loosen or tighten 90 the belt, after the manner of a slide.

Variations in details of construction are 100

permissible within the principle of the invention and the claim following.

What I claim is:—

An apparel buckle, composed of a frame, 5 having side bars, front and rear end bars, and cross bars between the end bars, with slots intervening between the end bars and said cross bars, and a hook-engaging cross bar at the front, the intervening cross bars 10 and the hook-engaging cross bar being depressed from the level of the frame, and another frame having a hook at its leading end to engage the hook-engaging cross bar to position the two frames in a common level.

15 In testimony whereof I have hereunto set my hand this ninth day of September, A. D. 1930.

ALLEN H. KERNGOOD.
